UNITED STATES PATENT OFFICE.

DANIEL KELLEHER, OF SANDUSKY, OHIO, ASSIGNOR TO HINDE & DAUCH PAPER COMPANY, OF SANDUSKY, OHIO.

PAPER-MAKING PROCESS.

1,203,008.

Specification of Letters Patent.

Patented Oct. 31, 1916.

Application filed July 10, 1916. Serial No. 108,312.

To all whom it may concern:

Be it known that I, DANIEL KELLEHER, a citizen of the United States, residing at Sandusky, Erie county, Ohio, have invented 5 certain new and useful Improvements in Paper-Making Processes, of which the following is a specification.

This invention, pertaining to paper-making processes, relates to process improvements by means of which a sheet of paper may be formed of desired thickness and with its fibers laid in an advantageous manner, the improved process also lending itself to the formation of seamless paper articles.

It is believed that my improved process will be best understood by first describing the construction and operation of an exemplifying device for executing the process, 20 and I have chosen for illustration, a machine for forming seamless paper cups. In usual processes for producing paper cups, a sheet of paper has been formed by usual paper-making process, the sheet being later 25 cut up into proper blanks and seamed up by adhesive methods. In my improved process such an article as a paper cup can be readily produced direct from pulp solution, and without seams in the article.

30 In the exemplifying drawings, Figure 1 is a diametrical section of a cup-forming screen, and immediate accessories, in the plane of line *a*, of Figs. 5, 3, 8 and 10: Fig. 2 a diametrical section of the inner wall of 35 the vacuum-pocket in the plane of line *a* of Figs. 3, 5, 8 and 10: Fig. 3 a bottom view of the inner wall of the vacuum-pocket corresponding with the lower end of the vacuum-pocket as it appears in Fig. 1: Fig. 4 a 40 vertical section of the vat and its contained mechanism, in the plane of line *a* of Figs. 3, 5, 8, 9 and 10: Fig. 5 an elevation of the cup-forming screen and its carrier, this view being a top view when considering Figs. 1, 45 6 and 10, and a bottom view when considering Fig. 4, and a horizontal view from the left when considering Fig. 8: Fig. 6 a side elevation of the cup-forming screen and its carrier: Fig. 7 an end view of the valve- 50 mechanism of the shaft of the carrier of the vacuum-pocket: Fig. 8 a vertical section of the vat and its contained mechanism in the plane of line *c* of Fig. 4: Fig. 9 an elevation of the valve controlling the vacuum in 55 the shaft of the vacuum-pocket carrier: Fig.

10 an end elevation of the carrier of the cup-forming screen: and Fig. 11 a vertical section of the exemplifying machine in the plane of line *c* of Fig. 4.

In the drawings, see Figs. 1, 2 and 3, 1, indicates a screen, illustrated as of frusto conical form suited for the formation within it of a paper cup: 2, a carrier for this screen, the open end of the screen, which is formed of an outer wire cloth member and an inner wire cloth member of finer mesh, being soldered to a ring secured to the carrier: 3, a vacuum cup surrounding the screen: 4, an inner wall for the vacuum cup, the inner surface of this inner wall coming close to but 70 free from the exterior of the screen: 5, a carrier for the vacuum-cup, which vacuum-cup is capable of rotation within its carrier: 6, a packing carried by the carrier 5 of the vacuum-pocket, around the top of the screen, 75 and adapted to be engaged by the carrier 2 of the screen: 7, a suction-pipe connected with the vacuum-pocket: 8, the vacuum-space within the vacuum-pocket, between its inner and outer walls, the suction-pipe connecting 80 with this vacuum space: 9, a narrow slot in the floor of the inner wall of the vacuum-pocket, this slot being diagonally arranged in the floor in such manner, preferably, as to trail so that, as the vacuum-pocket is rotated 85 the upper portion of the slot is to the rear of the lower portion: and 10, a narrow slot in the inner wall of the vacuum-pocket, this slot extending longitudinally of the wall and oblique to the axis of the vacuum-pocket in 90 such manner that, as the vacuum-pocket rotates, one end of the slot will be angularly in advance of the other end of the slot.

Looking at Figs. 1, 2 and 3, let it be assumed that screen-carrier 2 with the screen is entirely away from the vacuum-pocket and held in the left hand, and assume that the carrier 5 of the vacuum-pocket is held in the right hand and that the vacuum space 8 is under suction from pipe 7. If, 100 now, by proper manipulation, the screen be poked down into the vacuum-pocket and pressed home against packing 6, the suction will act through slots 9 and 10 and through the screen and act on any material which 105 may be within the screen.

Now, having the parts in the assumed position and condition, let the structure under consideration be immersed in a pulp solution. The solution will fill the screen, and, 110

if the vacuum-pocket be rotated, the suction-slots 9 and 10 will produce a zone of suction traveling around the exterior of the screen and around under the floor of the screen.

5 This suction manifestly tends to withdraw water from the solution and to cause fibers of the solution to hug the interior of the screen. The continued rotation of the vacuum-pocket causes additional deposits of pulp 10 upon the interior of the screen, and this will hold good until the accumulating deposits of pulp upon the interior of the screen have produced a thickness of paper sheet through which the suction cannot act. Owing to the trailing angularity of slots 9 and 10 the suction 15 acts in what might be called a dragging manner upon the exterior of the screen, thus facilitating the laying of the fibers around the interior of the screen. If, however, while the structure is immersed in the pulp-solution, and the fibers are being laid around the interior of the screen, the degree of immersion of the structure within the pulp-solution be repetitively varied then, mani- 20 festly, the fibers instead of being strung out in a purely circumferential manner upon the interior of the screen, will be strung out in a helicoidal course, and the fibers of one helicoidal course will cross that of the preceding course, the result being that the sheet of 25 paper formed within the screen is composed largely of fibers crossing each other, as distinguished from fibers laid strictly parallel with each other. If, now, the structure be removed from the pulp-solution, and the two carriers with their immediate parts be separated from each other, and the surplus pulp-solution be emptied from the screen, the screen 30 will contain a sheet of wet paper whose exterior form corresponds with the interior form of the screen. If the screen with its paper content be now subjected to drying air the paper will become dry and the article will shrink and may readily leave 35 the screen. In the above description of the mode of operation of the exemplifying devices illustrated in Figs. 1, 2 and 3, it has been assumed that the devices would be operated manually.

40 50 Description will now be given of an exemplifying machine for giving the proper motion to the parts which have been referred to.

Continuing with the drawings, 11, indicates 55 a vat adapted to have maintained therein a body of pulp-solution, the carrier 5 of the vacuum-pocket being in the form of a drum mounted on a shaft journaled in the vat: 12, a drying conduit extending 60 up from the vat to any extent desired, this conduit being illustrated as going upwardly and then horizontally and then downwardly: 65 sprocket-wheels on the shaft on which is mounted the carrier 5 of the vacuum-pocket: 14, endless chains engaging these

sprocket-wheels and passing through the drying conduit 12, suitable idle pulleys being provided for the guiding of these chains, and the screen-carrier 2 being secured to these chains in such manner that when the 70 chains bring the screen carrier to the carrier of the vacuum-pocket the screen will enter the pocket: 15, transmitting mechanism for giving continuous motion to the chains: 16, an air inlet to the upper portion of the drying conduit, this inlet being adapted to convey dehumidified air to the conduit: 17, slides carried by the ends of screen-carrier 2 and adapted for motion parallel with the axis of the screen, the chains 14 connecting 80 with the screen-carrier through the medium of these slides: 18, springs tending to urge the slides in a direction away from the open mouth of the screen: 19, rollers carried by the outside of the screen-carrier: and 20, 85 cam-tracks disposed within the vat and adapted to be engaged by rollers 19 of the screen-carrier, this cam being throated at the point where the screen-carrier approaches the drum in the vat. 90

Looking at Fig. 8, in which the screen and its carrier are assumed as moving toward the drum in the vat, the chains move the screen down to near the drum; the rollers 19 of the screen-carrier engage the entrance-throats of the cams; at this time the vacuum-pocket 3 is in position to receive the screen; the cams force the screen into the vacuum-pocket and into sealing relationship therewith; the drum, being driven by the chains, 100 carries the vacuum-pocket and its associated screen down into and through the pulp-solution; the cams maintain the proper association of the screen with the vacuum-pocket while they are passing through the pulp-solution; when these parts leave the pulp-solution the chains withdraw the screen with its contents upwardly and then entirely through the drying conduit; the article 105 within the screen becomes dry while passing through the drying conduit; the screen and its contained article passes out of the drying conduit and is inverted; the paper article, having shrunken, drops out of the screen; the screen goes on to again enter the 110 vacuum-pocket and be immersed in the vat to form another paper article, and so on and on.

While the associated vacuum-pocket and screen have been passing through the pulp-solution in the vat, a practical degree of vacuum has been maintained in the vacuum-pocket to serve in withdrawing water from the pulp lying against the inner surface of the screen, and the mechanism for accomplishing this will now be described. 120

Continuing with the drawings, 21, indicates a shaft journaled in the walls of the vat and having mounted on it the carrier 5 of the vacuum-pocket, and driven by the 125

chains 14 as has been described: 22, a passage extending longitudinally through this shaft and having connected with it the suction-pipe 7 of the vacuum-pocket: 23, a 5 suction-pipe connected with passage 22 and adapted for connection with appropriate devices for producing suction in the pipe: 24, a stationary register-valve engaging the open end of shaft 21 and serving to place 10 passage 22 of the shaft in communication with suction-pipe 23 at times and cut the passage off from communication with the suction-pipe at other times: and 25, a handle by means of which valve 24 may be angularly adjusted.

While the screen and vacuum-pocket are in association with each other, and are passing through the pulp-solution in the vat, the suction is acting on the vacuum-space 20 in the vacuum-pocket and withdrawing water from the layer of pulp-solution on the interior surface of the screen, and when the screen and vacuum-pocket leave the pulp-solution the suction will be cut off by the 25 register-valve 24, which may be adjusted angularly to suit the level of the pulp-solution in the vat and the time of sealing the screen to and unsealing it from the vacuum-pocket.

30 It may be here stated that, while the illustration shows the carrier 5 as being provided with but a single vacuum-pocket, and the chains as being provided with but a single screen, preferable practice will provide carrier 5 with a circumferential series 35 of vacuum-pockets and will provide the chains with a series of screens arranged in such manner that successive screens will be brought into proper association with successive vacuum-pockets, the shaft 21 being provided with a circumferential series of 40 longitudinal passages 22 so that suction will be applied to each couple of associated vacuum-pockets and screens as they pass 45 through the pulp-solution in the vat.

In the previous description of the apparatus as operated manually, it was stated that while the associated screen and vacuum-pocket were immersed in the pulp-solution the vacuum-pocket was given a motion of rotation and given a motion of varying degrees of immersion in the pulp-solution. In the automatic machine, as the associated screen and vacuum-pocket enter and pass 55 through and leave the pulp-solution in the vat, the degree of immersion manifestly increases as these parts enter the vat and decrease as they leave the vat. The means by which the machines give rotary motion to the vacuum-pocket will now be described.

Continuing with the drawings, and having special reference to Fig. 4, 26, indicates a bevel-gear loose on shaft 21: 27, a bevel-pinion engaging this gear and fast on suction-pipe 7 of the vacuum-pocket, which

suction-pipe is to have a swiveled connection with shaft 21: 28, a sprocket-wheel loose on shaft 21 and fast with bevel-gear 26: 29, (Fig. 11) a chain engaging sprocket-wheel 28: and 30, transmitting mechanism 70 for giving motion to chain 29.

Regardless of whether or not drum 5 may be in motion, chain 29 will bring about the rotation of the vacuum-pocket, and, if drum 5 be in motion, this chain will similarly rotate the vacuum-pocket and, as the transmission mechanism which rotates the vacuum-pocket on its axis is independent of the transmission mechanism which drives chains 14 and the drum, the speed of rotation of the vacuum-pocket on its axis may be suited to the most advantageous withdrawal of water from the pulp forming the lining of the screen.

It has been explained that the continuous 85 movement of chains 14 carries the screen to and into association with the vacuum-pocket, and causes these parts to pass through the pulp-solution in the vat, and separates the screen with its paper lining 90 from the vacuum-pocket, and carries the screen and its paper lining through the drying conduit to a point of discharge.

Continuing with the drawings (see Fig. 11), 31, indicates the position of the screen-carrier and screen when the chains shall have carried them through and out of the drying conduit and shall have inverted them: and 32, the paper article which, by reason of the drying operation in the drying 100 conduit, has shrunken and fallen out of the screen.

Claim is not herein made for the machine set forth in the exemplifying drawings as that machine forms the subject-matter of 105 United States Patent No. 1,179,840, granted April 18th, 1916, on my application.

I claim:

1. The improvement in paper-making processes which consists, in subjecting a 110 screen-surface to a body of pulp-solution stationary relative to the screen, applying suction over a narrow area to the surface of the screen opposite the surface which is subjected to the pulp-solution, shifting the 115 narrow suction-area relative to the screen and pulp-solution at substantially right angles to the length of the suction-area so that the suction acts upon portions of the screen successively, and successively repeating the shifting of the suction area relative to the screen and pulp-solution so that the suction acts repeatedly on the screen and pulp-solution, substantially as set forth.

2. The improvement in paper-making 125 processes which consists, in subjecting a screen-surface to a body of pulp-solution stationary relative to the screen, applying suction over a narrow area to the surface of the screen opposite the surface which is 130

subjected to the pulp-solution, shifting the narrow suction-area relative to the screen and pulp-solution at substantially right angles to the length of the suction-area so that the suction acts upon portions of the screen successively, causing the suction to act upon the screen in a direction trailing with reference to the direction of shifting of the suction-area, and successively repeating the shifting of the suction area relative to the screen and pulp-solution so that the suction acts repeatedly on the screen and pulp-solution, substantially as set forth.

3. The improvement in paper-making processes which consists, in subjecting a screen-surface to a pulp-solution, applying suction to the opposite side of the screen over a narrow area while the first side of the screen is being subjected to the pulp-solution, shifting the narrow suction-area relative to the screen at substantially right angles to the length of the suction-area, successively repeating the subjection of the screen to the pulp-solution and to the suction, removing the screen with its deposited pulp from further subjection to the pulp-solution and to the suction, and subjecting the screen while the deposited pulp is upon it to the action of drying air, whereby fibers from the pulp-solution are drawn to the first screen-surface and laid thereon and over each other and water is drawn therefrom through the screen and the pulp-formation is dried upon the screen, substantially as set forth.

4. The improvement in paper-making processes which consists, in immersing a screen-surface in a pulp-solution while the opposite surface of the screen is guarded from the pulp-solution, applying suction to the opposite side of the screen over a narrow area while the first side of the screen is being subjected to the pulp-solution, shifting the narrow suction-area relative to the screen at substantially right angles to the length of the suction-area, successively repeating the subjection of the screen to the pulp-solution and the suction, and varying the depth of immersion of the screen in the pulp-solution, whereby fibers from the pulp-solution are drawn to the first screen-surface and laid thereon and diagonally over each other and water is drawn therefrom through the screen, substantially as set forth.

5. The improvement in paper-making processes which consists, in subjecting a screen-surface to a body of pulp-solution stationary relative to the screen, applying suction over a narrow area to the surface of the screen opposite the surface which is subjected to the pulp-solution, shifting the narrow suction-area relative to the screen and pulp-solution at substantially right angles to the length of the suction-area so that the suction acts upon portions of the screen successively, and successively repeating the shifting of the suction area relative to the screen and pulp-solution so that the suction acts repeatedly on the screen and pulp-solution and continuing such action of the suction upon the screen and pulp-solution so long as the screen is subjected to the pulp-solution, substantially as set forth.

6. The improvement in paper-making processes which consists, in subjecting one entire surface of an uninterrupted screen to a body of pulp-solution stationary relative to the screen, applying suction over a narrow area to the surface of the screen opposite the surface which is subjected to the pulp-solution, shifting the narrow suction-area relative to the screen and pulp-solution at substantially right angles to the length of the suction-area so that the suction acts upon all portions of the screen successively, and successively repeating the shifting of the suction-area relative to the screen and pulp-solution so that the suction acts repeatedly on the screen and pulp-solution, substantially as set forth.

7. The improvement in paper-making processes which consists, in lodging a layer of pulp on one surface of a screen immersed in a pulp-solution, draining moisture from the deposited pulp by means of suction applied at the opposite surface of the screen, lodging successive layers of pulp on the first layer while the suction through the screen continues, withdrawing the screen and its accumulated pulp from the solution, applying drying air to the screen and the accumulated layer of pulp on the screen and removing the resulting dry paper formation from the screen, substantially as set forth.

DANIEL KELLEHER.
